DESIGN FOR AN ELECTRICAL TERMINAL PLUG

Thomas W. Drury, near Burr Oak, Mich., assignor to H. A. Douglas Mfg. Co., Bronson, Mich., a corporation of Michigan

Original application September 20, 1943, Serial No. 111,162. Divided and this application October 15, 1943, Serial No. 111,385

Term of patent 14 years

(Cl. D26—1)

To all whom it may concern:

Be it known that I, Thomas W. Drury, a citizen of the United States, residing near Burr Oak, in the county of St. Joseph and State of Michigan, have invented a new, original, and ornamental Design for an Electrical Terminal Plug of which the following is a specification, reference being had to the accompanying drawing, forming part thereof.

This is a division of my application Serial Number D-111,162, filed September 20, 1943, for an Electrical connector.

Figure 1 is a perspective view of the electrical terminal plug showing my new design;

Figure 2 is a side elevational view thereof;

Figure 3 is an end elevational view as seen from the left of Figure 2; and

Figure 4 is an end elevational view as seen from the right of Figure 2.

I claim:

The ornamental design for an electrical terminal plug, as shown.

THOMAS W. DRURY.
